UNITED STATES PATENT OFFICE

ANTONIO F. SARG, OF NEW YORK, N. Y., ASSIGNOR TO PEPPERELL MANUFACTURING COMPANY, OF BOSTON, MASSACHUSETTS, A CORPORATION OF MASSACHUSETTS

DESIGN FOR A BLANKET

Application filed February 2, 1931. Serial No. 38,525. Term of patent 14 years.

To all whom it may concern:

Be it known that I, ANTONIO F. SARG, a citizen of the United States of America, residing at New York city, in the county of New York and State of New York, have invented a new, original, and ornamental Design for Blankets, of which the following is a specification, reference being had to the accompanying drawings forming part thereof, in which,

In the drawings the cross hatching designates contrasting colors.

I claim:

The ornamental design for a blanket as shown and described.

In testimony whereof I subscribe my signature.

ANTONIO F. SARG.
